COMBINED CAN CLOSURE AND POURING SPOUT

Albert E. Burkhardt, 5 Sunnyfield, Rolling
Hills Estates, Calif. 90274

Filed Aug. 23, 1971, Ser. No. 174,284

Term of patent 14 years

Int. Cl. D9—07

U.S. Cl. D9—275

FIG. 1.

FIG. 2.

FIG. 3.

FIG. 1 is a perspective view of a combined can closure and pouring spout showing my new design;

FIG. 2 is a side elevational view; and

FIG. 3 is a top plan view thereof.

I claim:

The ornamental design for a combined can closure and pouring spout, as shown.
